UNITED STATES PATENT OFFICE.

ELTON A. WRIGHT, OF CHICAGO, ILLINOIS, ASSIGNOR TO F. H. NOBLE & COMPANY, OF CHICAGO, ILLINOIS, A CORPORATION OF ILLINOIS.

CRYSTAL DETECTOR.

Application filed August 22, 1925. Serial No. 51,765.

My invention relates to a crystal detector designed to adjustably hold a crystal of one or the other variety of those used in radio apparatus for rectifying broadcast electrical waves of radio frequency and of an amplitude modulated in accordance with the amplitude of an impressed wave of audio frequency to thereby produce a unidirectional current of corresponding audio frequency variation which, by means of a telephone, may be caused to give audible signals. The object of my invention is to provide a crystal support which may be conveniently manipulated to change the position of the crystal with respect to the "cat whisker," or other contact member in order to explore the surface of the crystal and quickly find a sensitive contact spot, and also to provide for a variation of the cat whisker upon the crystal. My invention is not limited to the use of any particular variety of crystal, other than that it is intended to be used with one, such as galena, in which sensitive spots lie in separated points which must be brought into contact with the metallic contact member of the conductor carrying the signals in order to rectify the radio frequency signals carried thereby, and it is particularly useful in connection with crystals in which a nice adjustment of pressure of the contact member upon the crystal is important. My invention resides in the mechanical construction of the device which I have provided to accomplish the purposes mentioned, the essential elements thereof being more particularly pointed out in the appended claim defining my invention.

In the drawing, Figure 1 is a top plan view of the detector; and Fig. 2 is a longitudinal section of the same in the plane indicated by the dotted line 2-2 of Fig. 1, looking in the direction indicated by the arrow.

Like reference characters indicate like parts in all the figures of the drawing.

My crystal detector is constructed as a self-contained unit adapted to be secured as a whole to a wall or panel of the radio set in which it is employed. Describing now the particular construction shown in the drawing, the frame includes a base plate 1 equipped with opposite binding posts 2-2^a which are threaded to engage nuts 3 by which the posts are secured to the base plate,

and thumb nuts 4-4^a for making the electrical connections of the detector circuit. The binding post 4, it may here be stated, is in electrical connection with the base plate 1 and the crystal, while the binding post 4^a is insulated from such parts and is in electrical connection with the cat whisker.

The crystal 5 is mounted in any suitable manner in a rotatable holder 6 pivoted on the base plate and formed with a peripheral gear 7 arranged to mesh with a worm 8 formed on a shaft 9 which is provided with a knob 9^a for turning it. In the present instance, the crystal is mounted by means of Wood's metal 10 in a metal cup 11 which is removably secured in the rotatable holder 6 by means of spring clips 6^a secured to the latter, to provide for change of crystals thus mounted.

The shaft 9 before mentioned is rotatably mounted in an ear 12 struck up from the base plate and a tubular flanged block 12^a which is secured to an opposite ear on the base plate. The outwardly projecting portion of the block is threaded to receive a clamping nut 12^b by means of which the detector may be secured to the panel 20 of the radio set.

The shaft 9 is equipped near one end with a cam disk 13 made of non-conducting material, such as bakelite. This disk is arranged to cooperate with the contact arm 14 of a rocking lever 15 pivotally mounted in a bracket 16 which is non-conductively mounted on the base of the detector and electrically connected with the binding post 4^a. The cat whisker 17, mounted on an arm 18 which projects from the rocking lever 15, is arranged to make contact with the crystal non-axially or off-center of its axis of rotation, and a spring 19 serves to maintain it in yielding contact with the crystal when a lower portion of the disk permits the cat whisker to rock towards the crystal. The distance of the contact point from the axis of rotation may be varied by bending the cat whisker slightly, or may be attained by offsetting parts of regular and symmetrical construction.

The binding posts 4-4^a being properly connected in circuit, it is obvious that by turning the knob 9^a the crystal will be very slowly rotated, while the contact point of the cat whisker will be alternately raised

2
and lowered to vary the pressure of the contact, a very precise and permanent adjustment being thus attained.

I claim:

- 5 A crystal detector for radio apparatus comprising a frame, a rotatable crystal holder and crystal mounted therein, a non-axially arranged contact member insulated from said holder and arranged to complete

the detector circuit through said crystal, and 10 a manually operable rotatable shaft, operatively connected with said holder to rotate it, one bearing of said shaft being formed in a tubular block fixed to the frame and said block being equipped with a clamping 15 nut, whereby the detector may be clamped to a supporting panel.

ELTON A. WRIGHT.
